UNITED STATES PATENT OFFICE.

PHILIP MUELLER, OF DECATUR, ILLINOIS, ASSIGNOR TO ADOLPH MUELLER,
TRUSTEE, OF DECATUR, ILLINOIS.

SCREEN.

Original application filed December 19, 1919, Serial No. 345,929. Divided and this application filed
January 29, 1921. Serial No. 440,944.

This invention relates to water purification, screens and method of making the same and has particular reference to screens for water strainers of the general type disclosed 5 in Letters Patent to Henry Mueller 894,035, granted July 21, 1908.

This application is a division from an application Ser. No. 345,929, filed by me December 19, 1919, being divided therefrom 10 under requirement of the Commissioner of Patents.

It is a purpose of this invention to provide a screen of this type which may be cheaply and expeditiously made; which is 15 strong and rigid; and which is so constructed as to ensure maximum life under working conditions.

In the following description of the present preferred embodiment of this invention the 20 above and other various objects and advantages of this invention will be more clearly brought out, the same being shown in the accompanying drawings, wherein:—

Figure 1 is a plan view of one form of 25 blank from which the screen of the strainer may be constructed.

Figure 2 is a side elevational view of my 30 improved screen attached to the rod which maintains the screen in position in the casting.

Figure 3 is a sectional view of a screen made of a single piece of metal drawn to 35 shape and then perforated.

Figure 4 is a sectional view showing the 40 lapped joint of the meeting edges of the screen blank leaves of Fig. 3.

Figure 5 shows another method of securing the screen to the retaining rod.

Referring to the drawings, wherein like 45 numerals represent like parts in the several views, my improved screen is constructed from a single blank of perforated sheet metal having a central portion and a plurality of radiating wings or leaves. The blank shown in Figure 1 resembles a Roman cross, in that it has a central portion 11 and four wings or leaves 12; but it is to be understood 50 that the screen may be made up from a blank having more or less than four leaves. Preferably, each of the wings or leaves increases in width toward its outer end, so that, when the screen is finally formed, the leaves will all

lie in the same plane when the leaves are 55 bent to form the finished screen.

The screen may be formed in any suitable manner, for example, in an ordinary punch press. This materially reduces the 60 cost of manufacture.

In forming my improved screen from the blank, the leaves 12 are bent toward each other about a mandrel with the corresponding edge of each leaf overlapping the adjacent edge of the next leaf. The leaves 12, 65 when in this position, are subjected to great pressure so that the layers of metal are compressed and the wall of the strainer brought to a uniform thickness throughout. By constructing the strainer in the manner described, the leaves reinforce each other along 70 the lines of the overlaps and a strainer of considerable strength is obtained.

The top or closed end of the screen is 75 dented at a central point, as at 13, so as to provide a small, centrally disposed recess or indentation for the reception of one end of a rod 14 which serves to support the screen in position, when used in a strainer of the 80 type shown in the Henry Mueller patent referred to.

It is to be noted that by connecting the retaining wire or rod 14 to the screen 15 in the manner described, there is no danger of the rod being forced out of place by the 85 pressure of the spring portion of the wire. The recess in the bulged portion 13 forms a pocket in which the solder and upper end of the rod 14 are firmly seated, and therefore, the adhesive power of the solder is not 90 solely relied upon to maintain the wire or rod 14 in place.

In Fig. 3 I have shown the screen as formed in a manner slightly different from that heretofore described. In this form the 95 screen is drawn from a blank 16 instead of being stamped out, and, after it is brought to proper shape is perforated; it being impracticable to first perforate and then draw a blank because of the danger of distorting 100 the perforations.

In Fig. 5 the screen is secured to the retaining rod 17 by crimping or spinning the tip 18 into a groove 19 formed in the rod, so as to lock the parts together.

The construction shown gives a screen 105 which has all of the desirable features of strength, and simplicity of construction,

while by practicing the method disclosed screens may be made at a minimum outlay of time and labor and a consequent reduced cost.

5. While I have shown a particular construction and method it will be understood that such changes as are within the range of mechanical skill may be made and still be within the range of my invention.

10. I claim:

1. A filtering screen comprising a substantially cone shaped receptacle formed from a blank having a central portion and a plurality of radiating leaves which increase 15 in width towards their outer ends, the leaves being bent towards each other to lap the edge of each leaf relative to the edge of the adjacent leaf.

2. A filtering screen comprising a central portion and a plurality of leaves radiating therefrom which increase in width towards their outer ends, said leaves having their edges over-lapping.

3. A filtering screen comprising a central portion and a plurality of leaves radiating therefrom which increase in width towards their outer ends, the leaves being bent towards each other with the edge of a leaf over-lapping the adjacent edge of the adjacent leaf.

4. A filtering screen comprising a central portion and a plurality of leaves radiating therefrom which increase in width towards their outer ends, the leaves being bent towards each other with the edge of a leaf over-lapping the adjacent edge of the adjacent leaf, the metal of the over-lapping edges of said leaves being reduced so that the walls of the screen are substantially of uniform 40 thickness.

5. A filtering screen having a longitudinally disposed overlapped section compressed to give greater rigidity to said screen.

6. A filtering screen having a longitudinally disposed and overlapped section of substantially the same thickness as the screen, and of greater rigidity than the body of the screen.

7. A filtering screen, having at spaced intervals a plurality of superposed layers of metal compressed to give rigidity thereto.

8. A filtering screen having at spaced intervals a plurality of superposed layers of metal compressed and disposed longitudinally thereof to give rigidity thereto.

9. A filtering screen, the wall of which is of uniform thickness throughout, having at spaced intervals a plurality of compressed layers of metal to give rigidity thereto.

10. A filtering screen comprising a central portion and a plurality of leaves radiating therefrom, said leaves having their edges overlapping.

11. A filtering screen comprising a central portion and a plurality of leaves radiating therefrom, said leaves having their edges overlapping and the metal of the overlapping edges of said leaves being reduced so that the walls of the screen are substantially of uniform thickness.

12. An article of the class described formed from a blank and having a portion formed of superposed layers of material compressed to reduce said portion to substantially the same thickness as said blank.

In testimony whereof I have hereunto set my hand.

PHILIP MUELLER.
